(57) **CLAIM**

The ornamental design for a connector interface for a cable, as shown and described.

DESCRIPTION

FIG. 1 is a perspective view of a connector interface for a cable of my new design.

FIG. 2 is a second perspective view of the connector interface for a cable of FIG. 1; and,

FIG. 3 is a third perspective view of the connector interface for a cable of FIG. 1.

The broken line showing of a connector interface for a cable represents unclaimed subject matter and forms no part of the claimed design.
